DESIGN FOR A GAME BOARD

Joe A. Fredriksson, San Francisco, Calif.

Application March 26, 1941, Serial No. 99,911

Term of patent 14 years

To all whom it may concern:

Be it known that I, Joe A. Fredriksson, a citizen of the United States and a resident of the city and county of San Francisco, State of California, have invented a new, original, and ornamental Design for a Game Board, of which the following is a specification, reference being had to the accompanying drawing, forming a part thereof.

The figure of the drawing is a perspective view of a game board showing my new design. Portions of the design are shaded for contrasting colors.

I claim:

The ornamental design for a game board, substantially as shown and described.

JOE A. FREDRIKSSON.
